UNITED STATES PATENT OFFICE.

OTTO HEBESTREIT, OF COLORADO SPRINGS, COLORADO.

DESIGN FOR A GLASS-HOLDING TRAY.

No. 39,557.

Specification for Design.

Patented Sept. 22, 1908.

Application filed June 6, 1908. Serial No. 437,202. Term of patent 14 years.

To all whom it may concern:

Be it known that I, OTTO HEBESTREIT, a citizen of the United States, residing at Colorado Springs, in the county of El Paso and State of Colorado, have invented a new, original, and ornamental Design for a Glass-Holding Tray, of which the following is a specification, reference being had to the accompanying drawing, forming part thereof.

The figure is a perspective view of a glass-holding tray showing my new design.

What is claimed is:—

The ornamental design for a glass-holding tray as shown.

OTTO HEBESTREIT.
